ADOLPHE AUBERT, OF NOGENT-LE-ROTROU, FRANCE.

Letters Patent No. 94,463, dated September 7, 1869.

IMPROVEMENT IN PROPELLERS FOR VESSELS.

The Schedule referred to in these Letters Patent and making part of the same.

To whom it may concern:

Be it known that I, ADOLPHE AUBERT, of Nogent-le-Rotrou, France, have invented a certain new and improved Spiro-Cylindrical Propeller for Vessels; and I do hereby declare the following to be a full, clear, and exact description, reference being had to the accompanying drawings.

The object of my invention is to impart to vessels which are moved by propellers either greater power or greater and more uniform speed than can be attained by the employment of the ordinary naked propeller-blade.

My improved propeller is constructed of any suitable metal, such as cast or wrought-iron, steel, copper, bronze, &c.; and

It essentially consists of the three following elements:

First, a shaft forming the continuation of the driving-shaft, or connected with the latter by a suitable intermediary.

Second, a helix or blade fixed to this shaft or axis, making one complete turn at its inner side, around the axis, and a half turn around the same at its periphery.

Third, a cylinder encasing the blade, and solidly united with or fixed to its periphery by suitable means, and having a diameter equal to its longitudinal axis.

The characteristic feature of my invention lies in the combination of these three parts, and especially in the fact that the cylindrical casing is solidly united with the helix for the purpose of shielding the latter from the eddies, currents, and other accidental causes which interfere with the operation of the propeller, and of preventing the loss of power absorbed by the centrifugal force developed at the circumference of the naked blade. By the employment of my improved propeller, the centrifugal force of the helix is confined within the cylindrical casing, and is thus utilized to increase the power or speed of the vessel.

The manner in which my invention is or may be carried into effect will be fully understood by reference to the accompanying drawings, in which—

Figure 1 represents a transverse vertical section of a propeller made in accordance with my invention, and

Figure 2 is a longitudinal central section of the same.

In order to produce the best results, the length of the cylinder *a* should be about equal to its diameter, and the helix *b* should be so constructed, that while that part of it which is fixed to the shaft *c* makes one com-

plete revolution around the axis, its periphery will make but a half revolution, as seen in figs. 3 and 4.

Instead of one helix, two or more blades may be employed, or two or more consecutive spirals, depending upon the tonnage of the vessel, and the power or speed to be imparted to it. In case two blades are employed, the second, *b*, should occupy the position indicated in red lines in fig. 2. A complete union is required between the helix and the cylinder, and to this end I employ a number of fastening-irons or stays, *d*, arranged as shown in the drawings or in any other suitable manner.

The cylindrically-cased propeller thus constructed is placed in rear of the vessel below the water-line, so as to be entirely immersed, and is fixed to the end of the revolving shaft *c*, which is put in motion by the driving-shaft of the engine.

When the propeller is put in motion, its helicoidal acts upon the water in the usual manner to produce the movement of the vessel. The cylinder *a* prevents the violent displacement of the water in a lateral direction, which is occasioned by the centrifugal force developed by the ordinary naked propeller-blade, by forcing the water taken in at its lower end to pass out from its opposite end and to be subjected to the whole pressure of the helix; and the centrifugal force is thus utilized to increase the movement.

I am aware that in some instances a propeller-screw has been enclosed within a cylinder, and this, therefore, I do not claim. The construction of the propeller-blade in the present case, however, is such that it makes but one complete turn or less at its inner side, and but one half turn or less, around the axis at its periphery, while the cylinder has a diameter equal to its axis; the combination of these parts in this manner producing greatly-improved results over what has heretofore been effected.

What I claim, therefore, and desire to secure by Letters Patent, is—

The combination and arrangement, with relation to each other, of the propeller-shaft, the helix or blade arranged thereon, and constructed in the manner specified, and the cylinder, with a diameter equal to its length, fixed to and encasing the blade, as and for the purposes shown and set forth.

In testimony whereof, I have signed my name to this specification, before two subscribing witnesses.

A. AUBERT.
